(57) **CLAIM**

The ornamental design for a tool kit, as shown and described.

DESCRIPTION

FIG. 1 is a top view of a tool kit, showing our new design; FIG. 2 is a top, front and side perspective view thereof; and, FIG. 3 is an end view thereof.

The views not shown form no part of the claimed design.

1 Claim, 3 Drawing Sheets

FIG. 1

FIG. 2

FIG. 3
